United States Patent Office

Des. 186,660
Patented Nov. 17, 1959

186,660

COMBINED FERMENTATION TANK AND SUPPORTING FRAME THEREFOR

John W. Maybaum, Chicago, and William A. Taylor,
Midlothian, Ill.

Application July 15, 1957, Serial No. 46,947

Term of patent 14 years

(Cl. D16—2)

FIG. 1

FIG. 2

FIG. 3

FIG. 4

Figure 1 is a perspective view taken from one end of a combined fermentation tank and supporting frame therefor embodying our new design;

Figure 2 is an elevational view of the opposite end thereof;

Figure 3 is a bottom plan view thereof; and

Figure 4 is a left side elevational view thereof.

The dominant features of our design reside in the full line portions of the drawing.

Figs. 2, 3 and 4 are shown on a reduced scale.

We claim:

The ornamental design for a combined fermentation

tank and supporting frame therefor, as shown and described.
